2 Claims

ABSTRACT OF THE DISCLOSURE

Disclosed herein are compounds of the formula

in which Z represents a disubstituted 1,3-dioxan-4-yl of formula

in which R¹ is an alkyl containing from one to eight carbon atoms and R² is an alkyl containing from five to eight carbon atoms.

The compounds induce sterility and methods for their preparation and use are disclosed.

RELATION TO OTHER APPLICATIONS

This application is a continuation-in-part of co-pending application Ser. No. 17,904, filed Mar. 9, 1970, now abandoned.

BACKGROUND OF THE INVENTION

This invention relates to new derivatives of 3-chloro-1,2-propanediol and to processes for their preparation.

The compounds of this invention have been found to possess valuable pharmacologic properties. For example, the present compounds, cause sterility in male mammals without diminishing libido or spermatogenesis. The combination of these pharmacologic properties with the inherent low toxicity of these compounds renders them useful agents for population control.

SUMMARY OF THE INVENTION

The compounds of this invention may be represented by formula I

(I)

in which Z represents a disubstituted 1,3-dioxolan-4-yl of general formula

in which R¹ is alkyl containing from one to eight carbon atoms and R² is alkyl containing from five to eight carbon atoms; or Z represents a substituted ethylene glycol group of formula

2

DETAILS OF THE INVENTION

The new derivatives of 3-chloro-1,2-propanediol of formula I of this invention have been found to possess useful pharmacologic properties. More specifically it may be demonstrated that the compounds of this invention are capable of causing sterility in standard pharmacologic tests, such as those described by K. T. Kirton et al., Fed. Proc. 28, 705 (1969) or by J. A. Coppola, Life Sciences 8, 43 (1969). In such tests it may be shown that the compounds of this invention do not interfere with normal libido, coitus and ejaculation. Furthermore, the compounds of this invention are able to effect reversible or permanent sterility depending upon the dose employed.

Recently, attention has been focused on the ability of 25 3-chloro-1,2-propanediol to cause sterility in male rats and other species, see Kirton and Coppola, both cited above. However, this property has been associated with a variety of toxic effects, for example, see S. A. Gunn et al. Proc. Soc. Exptl. Biol. Med., 132, 656 (1969).

30 It is the object of this invention to disclose new derivatives of 3-chloro-1,2-propanediol, compounds of formula I, which are able to elicit the capacity of 3-chloro-1,2-propanediol to cause sterilization in the host recipient by a much wider margin of safety.

35 More specifically, the compounds of this invention of formula I exhibit substantially the same minimum effective dose range on a daily basis, as 3-chloro-1,2-propanediol for inducing sterility. At this dosage, a reversible sterility is induced by all these compounds, and the host subsequently becomes fertile after cessation of the medication. At dosages five to ten times the minimum effective dose, a permanent sterility results on repeated daily doses. However, in contradistinction to 3-chloro-1,2-propanediol, the 40 compounds of this invention may be administered on a prolonged basis at dosages five- to ten-fold greater than their minimum effective dose with a 100% survival rate, whereas 3-chloro-1,2-propanediol, induces gross toxic effects and an eventual 100% mortality under similar conditions.

45 50 For example, both 4-(chloromethyl)-2-methyl-2-pentyl-1,3-dioxolane (I; in which Z is

55 and 3-chloro-1,2-propanediol induce reversible sterility in 60 rats at an oral minimum effective dose of 2.5 mg./day/rat when tested in the above standard pharmacologic tests. When the former compound, a compound of this invention, is administered orally to rats at 25 mg./day/rat for 20 days, sterility results but no effect is observed on 65 normal libido, coitus and ejaculation. After the medication is stopped all animals behave normally and enjoy good health; however, approximately one half of the group remain sterile ($ED_{50} \approx 25$ mg./day/rat for inducing permanent sterility). On the other hand, when the latter compound, 3-chloro-1,2-propanediol, is administered to rats at 25 mg./day/rat for 20 days under the same conditions, 70 none of the rats survive.

The substantially wide margin of safety found for the compounds of this invention is even more surprising since a related known compound, 4-(chloromethyl)-2,2-dimethyl-1,3-dioxolane, described by C. E. Ballow, Biochem. Preparations, 7, 45 (1960), is even more toxic than 3-chloro-1,2-propanediol.

The much wider margin of safety possessed by the compounds of this invention allows them to be used to advantage in the following ways. First, the compounds of this invention may be used as effective agents for the control of rodent populations. It is an advantage that larger doses of the compounds of this invention produce surviving sterile males still capable of mating, instead of causing their demise. Consequently, when these sterile males mate, they induce a state of pseudopregnancy in the female making the females unavailable for breeding with the still fertile male members of the colony.

Secondly, in cases where temporary sterility is desired for the purpose of population control the compounds of this invention may be used with a much greater assurance of safety due to the lower toxicity of these compounds.

When the compounds of this invention are employed as agents to induce sterility in warm-blooded animals, e.g. rats, they may be used alone or in combination with pharmacologically acceptable carriers. The preparation of these compounds is determined by the solubility and chemical nature of the compound, chosen route of administration and standard biological practice. For example, they may be administered orally in solid form containing such excipients as starch, milk sugar, certain types of clay and so forth. They may also be administered orally in the form of solutions or they may be injected parenterally. For parenteral administration they may be used in the form of a sterile solution containing other solutes, for example, enough saline or glucose to make the solution isotonic.

The dosage of the present therapeutic agents will vary with the form of administration and the particular compound chosen. Furthermore, it will vary with the particular host under treatment. Generally, treatment is initiated with small dosages substantially less than the optimum dose of the compound. Thereafter, the dosage is increased by small increments until the optimum effect under the circumstances is reached. In general, the compound of this invention are most desirably administered at a concentration level that will generally afford effective results without causing any harmful or deleterious side effects and preferably at a level that is in a range of from about 0.1 mg. to about 100 mg. per kilo per day, although as aforementioned variations will occur. However, a dosage level that is in the range of from about 1.0 mg. to about 20 mg. per kilo per day is most desirably employed in order to achieve effective results.

When the compounds of this invention are employed as rodent control agents they may be placed in a bait in which the active ingredient is present in a concentration of 0.01 to 2.0 percent. The bait consists of an edible carrier preferably a highly palatable food to rodents, and may be a mixture of corn meal, cracked corn, cereal grains, meat or fish scraps, bread crumbs, pellets of prepared cereals, vegetable oils, fish oils, powdered sugar, molasses, and such condiments as salt and spices. The bait thus prepared is placed in an accessible location in an area frequented by rodents.

The compounds of this invention of formula I, $Z-\text{CH}_2-\text{Cl}$, in which Z represents a disubstituted 1,3-dioxolan-4-yl of general formula

in which R^1 and R^2 are as defined above, may be prepared by treating the commercially available 3-chloro-1,2-propanediol, described by J. B. Conant and O. R. Quayle, "Organic Syntheses," Coll. Vol. I, John Wiley and Sons, Inc., New York, N.Y. 1941, p. 294, with a ketone of general formula $R^1R^2C=O$, in the presence of an acid catalyst, with or without the use of an inert solvent.

In the preceding reaction, the employment of perchloric acid as the acid catalyst is both effective and convenient. A reaction time of one hour to 72 hours, preferably 16 to 24 hours, and a reaction temperature of 0° to 100° C., preferably 15 to 35° C., are most suitable conditions for accomplishing this reaction. If it is desirable to use an inert solvent, either dioxane or chloroform may be used as the reaction solvent. Many of the ketones of general formula $R^1R^2C=O$ are commercially available. Methods for preparing and descriptions of these ketones may be found in organic chemistry textbooks; for example, "Rodd's Chemistry of Carbon Compounds," Vol. I, part C, 2nd ed., S. Coffey, Ed., Elsevier Publishing Co., Amsterdam, 1965, pp. 66-69.

The compound of this invention of formula I,

in which Z represents a substituted ethylene glycol group of formula

may be prepared by treating the commercially available 3-chloro-1,2-propanediol with dihydropyran in the presence of an acid catalyst, with or without the use of an inert solvent.

In the preceding reaction, the employment of phosphorus oxychloride as the acid catalyst is both effective and convenient. A reaction time of one hour to 72 hours, preferably 16 to 24 hours, and a reaction temperature of 0° to 100° C., preferably 15 to 35° C., are most suitable conditions for accomplishing this reaction. If it is desirable to use an inert solvent for this reaction, benzene, ether or tetrahydrofuran may be used as the reaction solvent.

The following Examples serve to illustrate further this invention.

EXAMPLE 1

A mixture of 2-heptanone (10.0 g.), 3-chloro-1,2-propanediol and perchloric acid (0.5 ml.) is allowed to stand at room temperature for 16 hours. Anhydrous potassium carbonate (1.0 g.) is added to the mixture, which is then subjected to filtration. The filtrate is distilled under reduced pressure to afford 4-(chloromethyl)-2-methyl-2-pentyl-1,3-dioxolane, b.p. 78-80°/10 mm., n.m.r. (CDCl_3) δ 3.5 (m, 2H) and 0.9 (d, 3H).

The procedure of Example 1 may be followed to prepare the compounds of formula I, listed below in Table I. In each case an equivalent amount of the appropriate starting material, a ketone of general formula $R^1R^2C=O$, is used instead of 2-heptanone.

TABLE I

Example	Ketone of Formula R ¹ R ² C=O		Product, compound of Formula I (Prefix listed below)-1,3-dioxolane
	R ¹	R ²	
2	C ₆ H ₁₁	C ₄ H ₉	2-butyl-4-(chloromethyl)-2-pentyl-
3	C ₆ H ₁₃	C ₄ H ₉	2-butyl-4-(chloromethyl)-2-hexyl-
4	C ₇ H ₁₅	C ₄ H ₉	2-butyl-4-(chloromethyl)-2-heptyl-
5	C ₈ H ₁₇	C ₄ H ₉	2-butyl-4-(chloromethyl)-2-octyl-
6	C ₂ H ₅	C ₆ H ₁₁	4-(chloromethyl)-2-ethyl-2-pentyl-
7	C ₃ H ₇	C ₅ H ₁₁	4-(chloromethyl)-2-pentyl-2-propyl-
8	C ₄ H ₉	C ₅ H ₁₁	2-butyl-4-(chloromethyl)-2-pentyl-
9	C ₅ H ₁₁	C ₄ H ₉	4-(chloromethyl)-2-dipentyl-
10	C ₆ H ₁₃	C ₅ H ₁₁	4-(chloromethyl)-2-hexyl-2-pentyl-
11	C ₇ H ₁₅	C ₅ H ₁₁	4-(chloromethyl)-2-heptyl-2-pentyl-
12	C ₈ H ₁₇	C ₅ H ₁₁	4-(chloromethyl)-2-octyl-2-pentyl-
13	C ₂ H ₅	C ₆ H ₁₃	4-(chloromethyl)-2-hexyl-2-methyl-
14	C ₂ H ₅	C ₆ H ₁₃	4-(chloromethyl)-2-ethyl-2-hexyl-
15	C ₃ H ₇	C ₆ H ₁₃	4-(chloromethyl)-2-hexyl-2-propyl-
16	C ₄ H ₉	C ₆ H ₁₃	2-butyl-4-(chloromethyl)-2-hexyl-
17	C ₅ H ₁₁	C ₆ H ₁₃	4-(chloromethyl)-2-hexyl-2-pentyl-
18	C ₆ H ₁₃	C ₆ H ₁₃	4-(chloromethyl)-2,2-dihexyl-
19	C ₇ H ₁₅	C ₆ H ₁₃	4-(chloromethyl)-2-heptyl-2-hexyl-
20	C ₈ H ₁₇	C ₆ H ₁₃	4-(chloromethyl)-2-hexyl-2-octyl-
21	C ₂ H ₅	C ₇ H ₁₅	4-(chloromethyl)-2-heptyl-2-methyl-
22	C ₂ H ₅	C ₇ H ₁₅	4-(chloromethyl)-2-ethyl-2-heptyl-
23	C ₃ H ₇	C ₇ H ₁₅	4-(chloromethyl)-2-heptyl-2-propyl-
24	C ₄ H ₉	C ₇ H ₁₅	2-butyl-4-(chloromethyl)-2-heptyl-
25	C ₅ H ₁₁	C ₇ H ₁₅	4-(chloromethyl)-2-heptyl-2-pentyl-
26	C ₆ H ₁₃	C ₇ H ₁₅	4-(chloromethyl)-2-heptyl-2-hexyl-
27	C ₇ H ₁₅	C ₇ H ₁₅	4-(chloromethyl)-2,2-dihexyl-
28	C ₈ H ₁₇	C ₇ H ₁₅	4-(chloromethyl)-2-heptyl-2-octyl-
29	C ₂ H ₅	C ₈ H ₁₇	4-(chloromethyl)-2-methyl-2-octyl-
30	C ₂ H ₅	C ₈ H ₁₇	4-(chloromethyl)-2-ethyl-2-octyl-
31	C ₃ H ₇	C ₈ H ₁₇	4-(chloromethyl)-2-octyl-2-propyl-
32	C ₄ H ₉	C ₈ H ₁₇	2-butyl-4-(chloromethyl)-2-octyl-
33	C ₅ H ₁₁	C ₈ H ₁₇	4-(chloromethyl)-2-octyl-2-pentyl-
34	C ₆ H ₁₃	C ₈ H ₁₇	4-(chloromethyl)-2-hexyl-2-octyl-
35	C ₇ H ₁₅	C ₈ H ₁₇	4-(chloromethyl)-2-heptyl-2-octyl-
36	C ₈ H ₁₇	C ₈ H ₁₇	4-(chloromethyl)-2,2-diethyl-

EXAMPLE 37

To a solution of 3-chloro-1,2-propanediol (1.0 g.) in 20 ml. of dry benzene, dihydropyran (1.4 g.) and one drop of phosphorus oxychloride are added. The mixture is allowed to stand at room temperature for 16 hours. The mixture is poured into ice water and extracted with ether. The ether extract is washed with water, dried and evaporated to dryness. The resulting residue is subjected to chromatography on silica gel. Elution of the column with

20% ethyl acetate in benzene yields 3-chloro-1,2-bis(tetrahydropyran-2-yloxy)propane, n.m.r. (CDCl₃) δ 4.6-4.8 (two doublets, 2H) and 1.6 (broad singlet, 12 H).

I claim:

5 1. A compound of the formula

wherein Z is a disubstituted 1,3-dioxolan-4-yl of formula

10 15 wherein R¹ is alkyl having from one to eight carbon atoms and R² is alkyl having from five to eight carbon atoms.

2. 4 - (Chloromethyl) - 2 - methyl - 2 - pentyl - 1,3-dioxolane, as claimed in Claim 1.
